UNITED STATES PATENT OFFICE.

MELVIN D. COMPTON, OF NEW YORK, N. Y.

SELF-STARTER FOR INTERNAL-EXPLOSION ENGINES.

1,123,173.

Specification of Letters Patent. Patented Dec. 29, 1914.

Application filed October 4, 1913. Serial No. 793,268.

To all whom it may concern:

Be it known that I, MELVIN D. COMPTON, a citizen of the United States, residing at New York, in the county of New York and 5 State of New York, have invented a certain new and useful Self-Start for Internal-Explosion Engines, of which the following is a specification.

The principal objects of the present invention are, first, to provide a self-contained and compact pneumatic rotary self-starter for internal explosion engines; second, to permit of hand cranking or starting; third, to insure response by the starter to its control; fourth, to cause the starter to operate successfully against compression in the engine cylinder and to withstand the action of back-fire whenever it may occur; fifth, to make the starter independent of and not affected by the starting of the engine under 10 its own power and the consequent movement of its parts; sixth, to avoid strain or reaction stress between the starter and engine when they are coupled together; seventh, to 15 cause the self-starter to remain quiet and at rest when not in use; and eighth, to cause the self-starter to spin the engine shaft continuously in one direction notwithstanding cylinder compression and possible back-fires 20 until the engine will run under its own power.

Generally stated, the invention consists of a combination of elements co-acting together and producing new and improved results 35 and obviating serious defects and disadvantages.

The invention will be claimed at the end hereof but will be first described in connection with the embodiment of it chosen for 40 illustration in the accompanying drawings in which—

Figure 1, is a side view, partly in section, of parts of an automobile equipped or fitted with a self-starter, embodying features of 45 the invention. Fig. 2, is a view drawn to an enlarged scale and showing in horizontal section a portion of the self-starter. Fig. 3, is a front view with parts removed and other parts shown in section. Fig. 4, is a 50 transverse sectional view. Fig. 5, is a horizontal sectional view, and Fig. 6, is a sectional view taken on the line 6—6 of Fig. 5.

In the drawings 1, is an internal explosion engine and in order to start it it has to be 55 spun and the effects of compression and back-fire have to be taken care of.

2, is the engine shaft.

3, is a starting shaft which has to be coupled with the engine shaft to start the engine and then rapidly and continuously rotated until the engine starts on its own power and finally disconnected from the engine shaft. The beveled ratchet clutch 4, and its pin 5, are interposed between the starting and engine shafts. 60

6, is an air tank or reservoir. 65

7, is an air pump or compressor driven by the engine and operating to accumulate or maintain a supply of air under pressure in the tank 6, when the engine is running by 70 its own power. The pump 7, is shown as connected with one of the engine cylinders and operated by the explosion that occurs therein.

8, is a pipe connecting the pump and tank. 75

9, is a starting cylinder adapted to receive air from the tank 6, by way of the connection 10, which is controlled as by a foot valve 11. This starting cylinder 9, is provided with a piston 12, which can be reciprocated by air from the tank 6. Roller-ratchet-mechanism is employed for converting reciprocation of the starting piston into continuous rotation of the starting shaft 3, in one direction and for preventing counter- 80 rotation which might be brought about should the engine back-fire and for permitting the engine to be cranked by hand as 85 will be explained.

13, is a housing connected with the cylinder 9, for inclosing the parts, and this housing and the cylinder 9 are shown as connected by means of a bracket 14 with the frame of the automobile. The piston rod 15, is provided with a fork, the arms 16 and 17 of 90 which work in guides in the housing 13. The fork arm 16 turns the roller-ratchet ring 18 back and forth and the fork arm 17 turns the roller-ratchet ring 19 back and forth. The roller-ratchet rings are mounted 95 around the roller-ratchet hub 20, shown as made in two parts connected together and provided with end flanges 21, which is a convenient construction for inserting the rollers 22 and 23, and retaining them in 100 place. The notches for the sets of rollers 22 and 23, are similarly disposed so that when the piston is moving toward the bottom of the sheet in Fig. 3, the fork arm 16 and the ring 18 and the rollers 22, are driving the hub 20 in clockwise direction and the 105 other set of roller-ratchet-mechanism is idle. 110

When the piston is moving in the other direction the fork arm 17 ring 19 and rollers 23, are driving the hub 20 in a clockwise direction and the other set of roller-ratchet mechanism is idle, thus the hub part is continuously rotated in one direction at high speed by a succession of impulses. The notches in disks 18 and 19 are staggered to insure inside end closure of each notch by the opposite disk. Furthermore a back-fire which would tend to turn the hub 20 counter-clockwise or the starting up of the engine with its fly-wheel effect which might tend to speed up the hub in clockwise direction do not throw the roller-ratchet-mechanism or any of its parts out of time and do not interfere in any way with their subsequent operation. The roller ratchet device which is not doing the driving operates to prevent counter-clockwise movement of the hub in the event of a back-fire. There is a spring-actuated-trigger release valve gear which in combination with the roller ratchet mechanism that prevents retrograde or backward turning of the starting shaft, compels the starting piston to make complete strokes independent of the state of compression in the engine cylinders and without requiring any fly-wheel effect.

24, is a slide valve for connecting the inlet port 25, with either of the cylinder ports 26 or 27 to drive the piston in one direction or the other. It also connects the cylinder ports 26 and 27 with the exhaust ports 28 and 29, as is well understood. The spindle 30, of this valve is provided with fixed enlargements or heads 31 and 32, having their inner ends beveled and their outer ends shouldered. On the spindle and between the heads there are two loose collars 33 and 34, with a spring 35 between them. Loose on the spindle is a housing 36, the ends of which inclose the collars 33 and 34. A tap-pet arm 37, movable with the piston and connected for example with the fork arm 17, strikes the ends of the housing 36. There are spring detents 38 and 39, carried by some fixed part of the device and adapted respectively to ride on the heads 31 and 32 and to engage the shouldered ends thereof. In any case the next movement of the valve 24, is restrained by one of the spring catches until the housing 36, acting on one of the collars has compressed the spring 35, and thereafter released the catch, thus permitting the valve to make its movement under the action of the spring whereupon it is locked by the other catch. For example in Fig. 3, the piston is moving upward and the next movement of the valve will be upward. The catch 38, engages the shoulder of the head 31. The arm 37, acting on the upper end of the housing 36, will cause the housing to compress the spring 35, and then the end of the housing releases the latch 38, with

the result that the spring will drive the valve upward. The catch 39 on the completion of the upward stroke will engage the shoulder of the head 32, locking the valve against downward movement until a repetition of the described movements but in the opposite direction has been completed.

40, is a sleeve upon which the hub part 20, is fast, and the shaft 3, extends through and is movable endwise in this sleeve.

41, is a coupling pinned to the shaft 3, and having sliding connection with the sleeve by means of the hexagonal shape of the coupling and of the part of the sleeve which it receives. Rotation of the hub 20, is transmitted to the shaft 3, through the sleeve and coupling and the coupling permits endwise motion of the shaft 3, in respect to the sleeve. This endwise motion permits the parts 4 and 5, to be engaged and disengaged. Evidently the shaft 3, can be pushed by means of a hand crank toward the right in Fig. 2, into engagement with the clutch member 4, against the force of the spring 50, which acts against a fixed collar on the car.

42, is a pneumatic piston opposed by a spring 43, and limited in its motion by a stop 44. This piston acts on the coupling 41, and in a cylinder 45, to which air is admitted from the tank 6, by way of the connection 46, whenever the valve 11, is opened and from which air exhausts when the valve 11, is closed by reason of leakage, for example at the valve 24. Air is admitted to the cylinder 45, slightly ahead of its admission to the cylinder 9. When air is admitted to the cylinder 45, it projects the piston 42, and the shaft 3, against the springs 43 and 50, thus coupling the shaft 3, with the engine shaft. The stop 44, prevents the piston 42 from exerting stress or strain between the engine shaft and the self-starter. In this way the self-starter is coupled up pneumatically with the engine shaft when the foot valve 11 is pushed, and is uncoupled by the action of the clutch 4 when the engine speeds up under its own power when the foot valve is released.

When the starter is not in use the spring 43, insures positive disengagement of the shaft 3, from the engine so that the starter remains at rest and quiet. The engine can be started by a crank applied to the front end of the shaft 3, which is pushed back so as to engage the engine shaft. When the foot valve 11, is pushed, air reaches the piston 42, and pushes the shaft 3, back into engagement with the engine shaft, but end pressure is not exerted thereon because the stop at 44, prevents such action. Air also reaches the cylinder 9, and starts the piston 12. This piston continues to make rapid and full strokes, being compelled so to do by the trigger-released-spring-actuated valve spin-

idle. The complete strokes of the piston 12, are imparted to the shaft 3, as continuous rotary motion in one direction regardless of back-fires, cylinder compression and the like by the roller-ratchet mechanism. When the engine has started, the foot valve 11 is released, the spring 43 disengages the self-starter from the engine shaft and the starter comes to rest.

10 It will be obvious to those skilled in the art that modifications may be made in details of construction and arrangement without departing from the spirit of the invention, hence the latter is not limited as to 15 those matters.

What I claim is:

1. A pneumatic self-starter comprising the combination of a starter shaft to be started and rapidly and continuously rotated and 20 which is provided with a clutch member, an air tank, a starting cylinder and piston operatively connected with the tank, roller ratchet mechanism for converting reciprocation of the piston into continuous rotation of the starting shaft in one direction and for preventing counter-rotation, spring-actuated-trigger-release valve gear operated by the reciprocation of the piston and compelling the same to make complete strokes, 25 30 spring retracted pneumatic means having a limiting stop and adapted to project and retract the starting clutch member, and means for admitting air from the tank to the pneumatic means and starting cylinder and for 35 excluding air from both, substantially as described.

2. In a self-starter the combination of a starting piston and cylinder, a starting

shaft, valve gear operated by the piston for compelling it to make full strokes in each 40 direction, and mechanism interposed between the shaft and piston for converting reciprocations of the piston into continuous rotary motion in one direction of the shaft and for preventing counter-rotation of the 45 shaft, whereby the shaft is locked against counter-rotation occasioned by back fire until the effect of the latter is over whereupon the starter resumes its rotation.

3. In a self-starter the combination of a 50 housing including a starting cylinder and guide ways, a piston having a forked piston rod guided by said guide ways, a starting shaft extending through the housing between the arms of the fork, a sleeve through 55 which the shaft is movable, a hub on the sleeve, roller-ratchet rings and their rolling bodies mounted on the hub and connected respectively with the fork arms of the piston to convert reciprocation thereof into rotation of the sleeve, a collar, a coupling cylinder formed at the rear of the housing and provided with a spring retracted piston and with a stop for the piston, a coupling 60 slidably and rotatably connected with the sleeve and fast on the starting shaft and in range of the coupling piston, and spring actuated trigger release valve gear for the starting piston arranged inside of the housing, and means connected with the starting 65 70 piston for actuating said valve gear.

MELVIN D. COMPTON.
